UNITED STATES PATENT OFFICE.

EDWARD A. C. HOGE, OF ELMHURST, NEW YORK, ASSIGNOR TO KEYSTONE FIREPROOF-
ING COMPANY, OF NEW YORK, N. Y., A CORPORATION OF DELAWARE.

BUILDING CONSTRUCTION.

1,171,400.

Specification of Letters Patent.

Patented Feb. 8, 1916.

Application filed May 3, 1915. Serial No. 25,389.

To all whom it may concern:

Be it known that I, EDWARD A. C. HOGE, a citizen of the United States, and residing at Elmhurst, Long Island, in the county 5 of Queens and State of New York, have invented a new and Improved Building Construction, of which the following specification is a full disclosure.

This invention deals with an improved 10 method of erecting the floor structures of buildings and it also proposes a novel and improved construction affording pronounced structural advantages over those heretofore in use.

15 A primary object is to create a roof or floor structure distinguished by an evenly distributed load-bearing capacity and in which the weight between the girders will be carried essentially by tension elements 20 combined with a number of compression elements disposed to relieve the outermost girders of accumulated lateral strains and combined also with a filler or matrix of light-weight plastic material.

25 Various other objects and advantages will be in part obvious from the annexed drawings and in part indicated in connection therewith by the following analysis of this invention.

30 This invention accordingly consists in the features of construction, of the end-bay and in the relative proportioning and disposition thereof and in the unique relations of the specially constructed end-bays with respect to the conventionally constructed middle bays, all as more completely outlined herein.

To enable others skilled in the art so fully to comprehend the underlying features 40 thereof that they may embody the same by the numerous modifications in structure and relation contemplated by this invention, drawings depicting a preferred form of my proposed structure have been annexed as a 45 part of this disclosure, and in such drawings, like characters of reference denote corresponding parts throughout all the views of which:

Figure 1 is a sectional perspective showing 50 a portion of a building constructed in accordance with this invention. Fig. 2 is a longitudinal section parallel with the suspension cables, and Fig. 3 is a section of an end bay of a floor embodying this invention.

In erecting a building in accordance with this invention, a plurality of purlins or floor-beams 1, 2, 3, etc., are suitably mounted on their ends by the walls or the outer framework of the building. These beams or 60 girders will preferably be formed of rolled steel in the form of I-beams or channel-beams; and they will be ranged in parallelism and spaced apart in accordance with the load to be sustained. The beams 1 and 65 2 constitute the side members of what is known as the end-bay of a building; the beam 1 representing in this instance the outermost element directly receiving the supporting strains, and the beam 2 being the 70 one next inward in the series. The beams 2 and 3 form an intermediate bay, and it is to be understood that a further succession of beams 3, 4, 5, etc., may be utilized to form an additional series of intermediate bays. 75 These beams constitute the major floor-supporting elements and this invention deals more particularly with the character and relation of the auxiliary elements and the manner in which they are combined with the 80 beams to form the floor proper. This invention contemplates what may be termed a three-element system for the end-bay span in combination with a two-element system for one or more of the intermediate bay 85 spans. That is to say, it proposes a strut, a tension-cable and a cast-matrix extending from the outermost beam 1 to the adjacent beam 2, all in combination with a tension cable and a cast-matrix between the beams 90 of an adjacent intermediate bay; all for the purpose of effecting a better distribution of the horizontally directed strains.

The preferred method of erecting this structure comprises the step (A) of interposing between the beams of an end-bay, a series of spaced strut-members forming compression elements which prevent the outer beam from being deflected inwardly 95 by bracing it laterally against the next innermost beam; the step (B) of laying a plurality of corrugated, roughened or patterned strands, wires or cables over the tops of the several beams and to attach one or more of these strands at their ends to the outermost or wall-beam 1, and to attach them at their other ends to one or another of the intermediate beams; the step (C) of initially deflecting each of these strand series at a point midway in each bay by 100 105 110

means of loads sufficient to bring them under normal strains; and then the step (D) of incasing these elements and filling in the intervening spaces with a composition 5 adapted to be cast or molded in place and capable of entering into a non-slipping union with the tension-strands to form a roof or floor. The various details of the 10 preferred mode of carrying out this erection may now be described.

To facilitate the carrying out of the final 15 step (C), it is desirable at the outset to assemble a cradle or mold in underlying relation with the girders 1, 2, 3, etc. so that the composition, while liquid, may be poured 20 into place to embed the girders and other elements and then set into hard permanent shape. This cradle mold may very conveniently be built up as shown by the drawings, by suspending a series of main joists 25 6 from the girders by means of joist-hangers 7 formed of steel rods or wire passing underneath the joists and over the girders as shown. A soffit-board 8 extends transversely to and rests upon the joists 6; each soffit-board being positioned to underlie the lower flange of its respective beam and to extend parallel therewith to form the bottom surface of the composition embedding the 30 beam. On each side of each girder is a haunch-board 9 which bears edgewise against the soffit-board so that its side extends upwardly either vertically or at an angle, to form the sides of the molded beam 35 incasing the girder. Extending between the haunch-boards of each span, are a series of beams 10 which are for the purpose of laterally supporting the haunch-boards and upon which may be laid the sheathing 40 boards 11, 12, etc., upon which the composition is poured. These beams 10 may in turn be suspended by cleats 13 fastened to the haunch-boards or resting upon the joists 6 as may be desired. It will be understood 45 that this structure is a temporary scaffolding in the nature of a mold-cradle which is assembled preparatory to casting the body portion of the floor, and this cradle is removed as soon as the floor-filling has sufficiently 50 set, and it also serves the purpose of forming an anchorage for drawing taut the tension cables, as will now be described.

The design of this floor construction is such that the weight is essentially carried 55 by certain tension-members in the nature of stretched strands and, although a filling composition which takes a permanent set is used, this composition is not depended upon for weight-carrying purposes so much as for giving shape, body and stiffness to the 60 structure as a whole. These tension-elements are formed of strands; certain or all of which are suitably secured to the outermost girder 1, preferably by means of suitable hooks attached to the upper flanges as 65

shown. These strands then pass successively over the various other girders to a point of attachment to one or the other of the more remote girders of the series. These tension elements are preferably in the nature of 70 cables composed of fairly heavy twisted galvanized steel wires. This twisted form is very advantageous in that it forms a cheap and inexpensive manner of obtaining a tension-element which is corrugated or 75 configurated in such a way that it will interlock with the material cast around it, thereby preventing any slipping from taking place between the tensioned cables and the filling after the latter has set. This makes 80 greatly for a solid and secure structure with well distributed strains. These twisted wire cables 14 are spaced apart at appropriate intervals and a deflection rod 15 is then laid upon the cables at the middle point 85 of each bay or span and this deflection rod is then drawn downwardly so as to impose more or less normal strains on the cables 14. A convenient and satisfactory manner of bearing down on this deflection rod is to 90 pass a steel wire 16 around the beam 10 and to bring its upper ends around the deflection rod 15 and twist the loose ends together until a sufficient downward pull has been exerted on the deflection rod 15. By 95 this arrangement, an identical load is placed on the suspension cables at each bay and each of the intermediate girders will carry an equal downward load but, inasmuch as the ends of the strands are ultimately secured 100 to the outermost girders, this gives rise to a tendency for the outermost girders to be deflected inwardly, but this load is also equalized and distributed by means of this invention which contemplates the utilization of a 105 local series of strut elements between the girders of the end-bay and in certain instances between the girders of the adjacent bay also, but not between the girders of the intermediate bays. These local strut-members 110 may be formed of iron-pipes 17 placed initially between the girders 1 and 2, preferably closely adjacent the upper edge margins thereof, and preferably wedged therebetween either by being cut to exact 115 length or more conveniently by utilizing a wedge-block 18 at one end thereof which is driven in place by means of a hammer. These strut-members will be proportioned and spaced so as to carry the lateral deflecting loads imposed in the first instance on the girder 1 under the pull of the cables (which load will amount to a maximum of about 160 pounds per cable in many instances of construction) and to transmit a 120 material proportion of the load to one or more of the adjacent intermediate girders. By combining these true compression elements with the true tension elements above noted, a well reinforced structure will be 125 130

produced in which no undue loads will be imposed upon any given girder and in which the pull of the cables will be carried by two or more of the outermost girders instead of 5 by the wall-girder alone.

Having thus prepared the parts as above indicated, all of the enumerated elements are ready to be sheathed and all intervening spaces to be filled by pouring a lightweight 10 plastic fire-resisting material, such as plaster of Paris or other composition, into place and then allowing it to set. Sufficient of this material will preferably be poured in place to cover the tops of the girders and after it 15 has been set the cradle may be removed by cutting the wires 7 and 16 and trimming off loose ends thereof. In place of plaster of Paris any other composition may be employed, although gypsum is preferred as it 20 is the lightest and most satisfactory floor material now cheaply purchasable, and this construction is such that it is structurally available although it does not possess the strength of Portland cement.

Without further analysis, the foregoing 25 will so fully reveal the gist of this invention that others can by applying current knowledge readily adapt it for various applications without omitting certain features that, 30 from the standpoint of the prior art, fairly constitute essential characteristics of the generic or specific aspects of this invention, and therefore such adaptations should and are intended to be comprehended within the 35 meaning and range of equivalency of the following claims.

A distinct advantage of this construction lies in the fact that although plaster of Paris does not possess the high compressive 40 strength of Portland cement, nevertheless, it does have a considerable compressive strength which exercises a valuable function in supporting loads and which enters permanently into action in bracing the compression members 45 17 against lateral deflection. Consequently the relatively thin or narrow elements will suffice by reason of the coöperation of the plaster of Paris which prevents any buckling thereof.

Having thus revealed this invention, I 50 claim as new and desire to secure the following combinations of steps and elements, or equivalents thereof, by Letters Patent of the United States:—

1. A floor structure combining a plurality of girders spaced apart to form an end-bay, and a number of intermediate bays, a series 55 of spaced compression members interposed between the girders of the end-bay and bearing against the outermost girder at or adjacent the upper flange thereof for resisting the overturning of said girder, a series of

tension cables attached to the outermost girder of the end-bay and extending successively over the intermediate girders, means located 65 at and intermediate of each bay for bearing down on the loops of said cables, and a cementitious fire resisting matrix embedding all of said elements and forming the body of the floor. 70

2. A floor structure combining a plurality of girders spaced apart to form an end-bay, and a number of intermediate bays, a series 75 of spaced compression members interposed and terminating between the girders of only the end-bay, the ends of said members engaging the girders substantially at their upper flanges, a series of tension twisted-wires attached to the outermost girder of the end-bay and extending successively over the 80 intermediate girders, means located at and intermediate of each bay for bearing down on the loops of said twisted-wires, and a matrix of plaster of Paris embedding all of 85 said elements and forming the body of the floor.

3. A floor structure combining a plurality of girders spaced apart to form an end-bay and a number of intermediate bays; a series 90 of spaced straight compression members interposed and terminating between the girders of only the end-bay, the ends of said members being spaced away from the lower flanges of said girders; a series of tensioned twisted-wires attached to the outermost 95 girder of the end-bay and extending successively over the intermediate girders; means located at an intermediate point of each bay for bearing down on the loops of said twisted wires; and a matrix of plaster of 100 Paris embedding all of said elements and forming the body of the floor.

4. A floor structure combining a series of girders spaced to form an end-bay and a number of intermediate bays; a plurality of 105 struts spaced laterally between the girders of the end-bay and positioned closely adjacent the upper edges of said girders and wedged therebetween; a series of spaced tensioned twisted-wires secured to the upper 110 edge of the outermost girder and extending successively over the upper edges of the intermediate girders; means applied to an intermediate point of each loop drawing said twisted-wires taut in each bay; and a matrix 115 of plaster of Paris embedding said elements and forming the body of the floor structure.

In witness whereof, I hereunto subscribe my name, as attested by the two subscribing witnesses.

EDWARD A. C. HOGE.
